KNIFE SHARPENER

Finn B. Abramsen, Whitehall, Pa.

Application September 7, 1950, Serial No. 183,635

5 Claims. (Cl. 51—208)

1

This invention relates to improvements in means for sharpening knives and the like; more particularly to manually operable sharpening means having a pair of abrasive stones for putting a fine edge on a knife or similar implement.

An object of my invention is to provide an abrasive sharpening means for knives and the like which is effective, simple in construction, rugged, easy to use, and low in cost so as to be suitable for general household use as well as for other uses. An ancillary object of my invention is to provide a knife sharpener which can be secured to any convenient wall or can be mounted on a small portable board or the like.

In accordance with the presently-preferred form of my invention, the sharpening means includes a knife-sharpener mechanism built around a springy yoke that is somewhat in the form of a U-shaped member having legs with offset portions. Each offset portion rotatably carries a frusto-conical roller in the nature of a grinding stone. The axes of the rollers are at suitably disposed angles for sharpening the edge of an implement drawn along their surfaces. The yoke has guiding means that holds the edge properly with respect to the rollers.

Another object of my invention is to provide a knife sharpener which causes the knife-edge and sharpening rollers to press against each other for more effective sharpening.

Objects, features, and innovations of my invention, in addition to the foregoing, will be discernible from the following description of a preferred embodiment thereof. The description is to be taken in conjunction with the accompanying drawing in which:

Fig. 1 is a top view showing a knife-sharpener embodying the principles of my invention, carried on a portable support;

Figs. 2 and 3 are a front view and a side view, respectively, of the sharpener on a support; and

Fig. 4 is an enlarged sectional view of the sharpener on the line IV—IV of Fig. 1.

A complete sharpening device embodying my invention comprises a knife-sharpener mechanism and a support therefor, identified in Fig. 1 by the reference numerals 2 and 4, respectively. In this particular embodiment, the device is intended to be hand-manipulatable, so that it carries a suitably shaped handle 6 which can easily and firmly be grasped and held in one hand of a person. The knife-sharpener mechanism 2 comprises a yoke 8, formed from a single piece of metal. As better shown in Fig. 2, the yoke 8, in front view, has a generally U-shape and comprises a base 10 and a pair of spaced facing leg

members 12 and 14 having a width adequate to accommodate the knife-sharpening rollers subsequently described.

The base 10 is slightly convex upwardly about an axis parallel to the leg members 12 and 14, so that the yoke has a pair of curved narrow supporting portions 16 and 18 which contact and rest on any suitable flat support indicated at 20 in Figs. 2 and 3, while the central part of the base is raised from the support. The supporting portions 16 and 18 are at the part of the yoke where its leg members 12 and 14 merge into its base 10; so that these supporting portions are, in effect, pivots on which the leg members can turn to a limited extent. The yoke 8 is secured to the support 20 by a pair of screws 22, or the equivalent, passing through the holes at opposite ends of the base 10. The holes are centrally in the curved or convex portion of the base.

The leg members 12 and 14 rotatably carry abrasive sharpening rollers 24 and 26, respectively, made from a suitable abrasive. To this end, the leg members 12 and 14 are provided with offset portions 28 and 30, respectively, one of which slopes to the right and the other to the left when the knife-sharpener mechanism 4 is viewed sidewise. Each offset portion has an inner lug 32 and an outer lug 34 bent over from the main portion of the associated leg member and extending in a direction toward the other leg member. Each pair of lugs 32 and 34 on an offset portion rotatably carries a knife-sharpening roller on a shaft, identified as 36 for the leg member 12 and as 38 for the leg member 14. The shafts 36 and 38 support the sharpening rollers 24 and 26 respectively. The rollers are frusto-conical in shape. It is to be noted that the arrangement of the lugs is such that shafts 36 and 38 lie in parallel planes but in lines that slope in opposite directions; and the rollers are supported on the shafts so that their larger bases are at lower points of the shafts as compared to the location of their smaller bases. As a result the larger bases face outwardly.

The offset portions 28 and 30 of the leg members 12 and 14, and the lugs 32 and 34 of the offset portions position the tapered rollers 24 and 26 so that the rollers are spaced apart, as better shown in Fig. 1, in the direction in which a knife is drawn through the knife-sharpener mechanism 2 for sharpening, and so that the operable surface-portions of the rollers that are to be contacted by the knife-edge are at an angle to each when observed, as seen in Fig. 2.

The knife to be sharpened is drawn through the knife-sharpener mechanism 2 in a path which places its edge between and substantially parallel to the parallel planes including the shafts 36 and 38. The faces of the rollers 24 and 26 have a slight taper and overlap slightly so that contact between the knife-edge and the faces is assured. As the knife-edge is drawn across the faces, it frictionally slides in contact with them, but the slope of the shafts and faces causes slow rotation of the rollers, so that they wear evenly. To some extent the degree of pressure between the rollers, on the one hand, and the knife, on the other hand, is controlled by the operator. When a knife is forced between the rollers 24 and 26, the leg members 12 and 14 are forcibly spread, turning on the support portions 16 and 18 of the yoke 8, as indicated by the broken lines in Fig. 2. The resilient characteristics of the yoke cause the leg members to tend to move back to unbiased position, so that they press on a knife-edge preventing this restoring movement.

For further guiding the movement and position of the knife-edge, the outer lugs 34 on the offset portions 28 and 30 of the leg members 12 and 14 have guide extensions 44 and 46, respectively. These guide extensions have abutment edges 48 and 50 that slant in opposite directions; each abutment edge sloping downwardly or inwardly towards the associated sharpening roller. These abutment edges keep the knife-edge along substantially a straight line in proper angular contact with the faces of the rollers 24 and 26, as the knife is drawn through the knife-sharpener mechanism 2 and prevent the knife from being pressed down through the rollers on to the base 10.

The small size and simplicity of the knife-sharpener mechanism permits it to be mounted to suit any appropriate use. Fig. 1 shows the implement as portable, so that it can be held in one hand while a knife is drawn through it by the other hand for sharpening. Obviously the yoke 8 can be fastened to a board or wall in a permanent position for convenient use.

While I have used the presently preferred form of my invention to describe the principles and teachings thereof, it is to be understood that it may be otherwise embodied within the scope of the appended claims.

I claim:

1. A knife sharpener comprising guide means for guiding an edge to be sharpened along a path, a pair of frusto-conical abrading rollers spaced along said path, a resilient supporting member for each roller, said supporting members being spaced along the path, each supporting member comprising a pair of spaced lugs extending toward the other of said supporting members, each of said pairs of lugs having means for rotatably carrying the associated roller with a face of the roller along said path, and with the axis of the roller at an angle to said path, the axis of said rollers lying in spaced substantially parallel planes having said path therebetween.

2. A knife sharpener comprising guide means for guiding an edge to be sharpened along a path, a pair of frusto-conical abrading rollers

spaced from each other along said path and with their larger bases facing in opposite directions, supporting means for rotatably supporting said rollers with their face surfaces on opposite sides of the path and at an angle thereto, said supporting means also being resilient whereby the rollers are resiliently pressed in a direction towards said path.

3. A knife sharpener comprising guide means for guiding an edge to be sharpened along a path, a pair of frusto-conical abrading rollers spaced along said path, a resilient supporting member for each roller, said supporting members being spaced along the path, each supporting member comprising a pair of spaced lugs extending toward the other of said supporting members, each of said pairs of lugs having means for rotatably carrying the associated roller with a face of the roller along said path, and with the axis of the roller at an angle to said path, the axis of said rollers lying in spaced substantially parallel planes having said path therebetween, one lug of each of said pairs of lugs extending across and beneath said path and upwardly on the side of the path opposite to the roller which the lug supports to provide said guide means.

4. A knife sharpener for sharpening an edge, comprising a resilient U-shaped support having a base and leg members, a frusto-conical abrasive roller rotatably mounted on each leg with the axes of said rollers lying in substantially parallel planes but spaced from each other in a direction along a sharpening path for said edge through said mechanism, said axes lying on different sides of said path and slanting in different directions and being resiliently urged in a direction towards said path by said support.

5. A knife sharpener for sharpening an edge, comprising a resilient U-shaped support having a base and leg members, a frusto-conical abrasive roller rotatably mounted on each leg with the axes of said rollers lying in substantially parallel planes but spaced from each other in a direction along a sharpening path for said edge through said mechanism, said axes lying on different sides of said path and slanting in different directions and being resiliently urged in a direction towards said path by said support, each leg member also having a lug extending across and beneath said path and upwardly on the side of the path opposite to the roller supported by said leg member, said lugs forming guides for a knife along said path.
